CLAIM

The ornamental design for an enclosure with movable portions, as shown and described.

DESCRIPTION

FIG. 1 is a rear-left perspective view of an embodiment of an enclosure with movable portions.

FIG. 2 is a front-right perspective view of the embodiment of FIG. 1.

FIG. 3 is a rear-right perspective view of the embodiment of FIG. 1.

FIG. 4 is a front-left perspective view of the embodiment of FIG. 1.

FIG. 5 is a front elevational view of the embodiment of FIG. 1.

FIG. 6 is a rear elevational view of the embodiment of FIG. 1.

FIG. 7 is a left elevational view of the embodiment of FIG. 1; and,

FIG. 8 is a right elevational view of the embodiment of FIG. 1.

The broken lines represent structure or features that form no part of the claimed design.

1 Claim, 8 Drawing Sheets
